ABSTRACT OF THE DISCLOSURE

A limiting network is described in the environment of current mode threshold logic gates. A threshold logic gate in accordance with various input signal combinations selectively distributes current to a pair of current carrying lines across which the limiting network is coupled. The limiting network includes a pair of transistors having their collector-emitter paths connected across the lines and their base electrodes coupled to a clamp voltage V_{CL} .

CROSS-REFERENCE

An application, Ser. No. 633,825, entitled Logic Circuitry, filed on Apr. 27, 1967, by Robert O. Winder and assigned to the present assignee, describes logic circuit stages useful in threshold logic as well as other logic circuits with which the present invention may be employed.

BACKGROUND OF INVENTION

Limiting networks are useful in many electronic circuits to prevent excessive current and/or voltage from causing component breakdown, undesired transistor saturation, excessive power dissipation and other undesirable effects. In one prior art application, namely, current mode threshold logic gates, it is desirable to prevent transistor saturation. In such gates, current is distributed between a pair of current carrying lines according to various input signal combinations. The gates generally include a number n of input current mode switch (CMS) comparators for selectively distributing current to the lines, a summing impedance for each line, and a CMS comparator for comparing the summed currents.

Each CMS comparator includes at least two transistors, one of which is controlled by an associated input signal and the other of which is controlled by the reference voltage V_{ref} . The collector electrodes of the CMS input transistors are commonly connected to one of the current carrying lines; while the collector electrodes of the CMS reference transistors are connected to the other current carrying line. The two transistors share a common emitter circuit in which a current source is connected. The current source may be simulated by a source of operating potential and a common current path such as a resistor. According to whether the applied signal voltage is above (more positive than) or below (more negative than) V_{ref} , each input comparator routes the current source current to one or the other of the current carrying lines. Separate summing impedances are connected to each of these lines to sum the current contributions provided by the CMS transistors. For some input signal combinations, these summed current contributions cause the output lines to assume voltages which may cause the saturation of either the input or output CMS comparator transistors.

The present invention relates to a limiting network which maintains a minimum current flow in a pair of current carrying lines, while preventing excessive current flow in either of the lines. In particular, the invention is useful in current mode threshold logic gates to prevent undesirable transistor saturation.

BRIEF SUMMARY OF INVENTION

According to one example of the invention, the limiting network includes a pair of transistors having their collector-emitter paths connected across the lines. The 5 base electrodes of the transistor pair are coupled to a clamping voltage V_{CL} . For cases where the current distribution between the lines is fairly even or differs only slightly (as for example, by one unit of current where each comparator supplies one or more units depending upon its weight), neither of the transistor pair is turned on. When the input signal combinations cause a more unbalanced current distribution thereby causing the voltage of one of the lines to vary below V_{CL} , one of the 10 transistor pair turns on to draw current from one line and supply current to the other line in such a manner as to prevent further voltage variations despite more extreme current distribution.

According to another example of the invention, a control circuit is provided for obtaining the clamping voltage 20 V_{CL} . The control circuit includes a comparator having three transistors arranged in an emitter-coupled current mode configuration. Two of these transistors are controlled by the voltages across the summing impedances; while the third transistor is connected to a reference voltage V_R . The clamping voltage V_{CL} is obtained from the collector electrode of the third transistor. As the voltage across one of the summing impedances varies above V_R , V_{CL} varies in a direction tending to turn on one of the 25 limiting network transistor pairs. As the current distribution becomes more extreme, the clamping voltage V_{CL} varies even more in the direction which tends to make the on one of the transistor pair conduct even more current, thereby tending to stabilize the voltages of the 30 current carrying lines.

BRIEF DESCRIPTION OF DRAWINGS

FIG. 1 is a schematic circuit diagram of the limiting network according to the present invention in the environment of a current mode threshold logic gate, and

40 FIG. 2 is a circuit diagram of a further embodiment of the invention.

DESCRIPTION OF PREFERRED EMBODIMENTS

45 Limiting networks according to the invention may be constructed either with discrete components or by means of integrated circuit processes. As used herein, the term, "integrated circuit," refers to those technologies by which an entire circuit can be formed as by diffusion or by films in or on one or more chips of materials, such as silicon, 50 glass, sapphire, and the like.

While not limited to any particular application or circuit environment, the limiting network of the present invention is illustrated, by way of example, in a current mode threshold logic circuit. Referring now to FIG. 1, there is illustrated a current mode threshold logic circuit wherein the limiting network according to the invention is illustrated generally at 20 as being connected between a pair of current carrying conductors or lines 17 and 18. The term, line, as used herein and in the appended claims 55 is intended to mean a connector or conductor of negligible or incidental impedance. That is, the line may have impedance due to the nature of the material used to implement the line; but such impedance is incidental to the connecting and current carrying functions of the line. For example, an integrated circuit array may employ appropriately shaped diffused regions of semiconductor material to effect connector cross-overs. These diffused connector regions generally have more resistivity or impedance than a metallic connector; but this impedance is incidental to the connecting function.

70 The limiting network 20 includes a pair of transistors

21 and **22**. The collector electrode **21c** and the emitter electrode **22e** are connected together and to line **17**; while the emitter electrode **21e** and the collector electrode **22c** are connected together and to the line **18**, thereby forming a parallel collector-emitter path combination for the two transistors. The base electrodes **21b** and **22b** are connected by way of separate base resistors **23** and **24**, respectively, to a common clamping line **25**. The clamping line **25** is connected to receive a clamping voltage designated V_{CL} .

In the current mode threshold logic circuit the current carrying lines **17** and **18** are the output lines for a number n of current mode switch (CMS) input comparators designated **10₁**, **10₂**, . . . and **10_n**. Each of the comparators has an associated input signal line **19₁**, **19₂**, . . . **19_n** each connected to receive an associated input signal X_1 , X_2 . . . and X_n , respectively. Since each of the CMS comparators is substantially identical, only the CMS comparator **10₁** will be described in detail. The comparator **10₁** includes a pair of transistors **11** and **12** having their emitter electrodes **11e** and **12e** connected in common and by way of an emitter resistor **13** to a power supply line **16**. The power supply line **16** is connected to receive a source of operating voltage designated V_{PS} , which source may be a battery. The base electrode **11b** is connected to the comparator input line **19₁** to receive the input signal voltage X_1 . The base electrode **12b** is connected to a reference voltage line **15** which is connected to receive a reference voltage designated V_{ref} . The reference voltage V_{ref} may be derived by any suitable means, for example, by way of a voltage divider arrangement from the power supply voltage V_{PS} . The collector electrodes **11c** and **12c** are connected to the output lines **17** and **18**, respectively.

Each of the other comparator circuits is connected in a like manner to the V_{PS} line **16**, the V_{ref} line **15** and the common output lines **17** and **18**. The collector circuits for all of the comparators are completed by way of load impedances **31** and **32** which connect the output lines **17** and **18**, respectively, to a supply line **30**. The supply line **30** is arbitrarily considered as the ground reference for the threshold logic circuit.

The function of discrimination or comparison with threshold is performed by a discrimination circuit **35**. The circuit **35** has a pair of inputs **36** and **37** connected to the output lines **17** and **18**, respectively, and a pair of output terminals **38** and **39**, also designated V_0 and $\bar{V}_0$, respectively.

Discrimination circuit **35** is illustrated as an output CMS comparator having a pair of CMS transistors **40** and **41**. The base electrodes **41b** and **40b** are connected to the input lines **36** and **37**. The emitter electrodes **40e** and **41e** are connected together and by way of common emitter resistor **42** to the supply voltage V_{PS} . The collector electrodes **40c** and **41c** are connected by way of separate collector resistors **43** and **44** to the ground line **G**. The collector electrodes of the CMS transistors **40** and **41** are further connected to the base electrodes **45b** and **46b** of a pair of output emitter-follower transistors **45** and **46**. The emitter-follower transistors **45** and **46** each have their collector electrodes **45c** and **46c** connected to the ground line **G** and their emitter electrodes **45e** and **46e** connected by way of emitter resistors **47** and **48** to the V_{PS} supply line. The output terminals **38** and **39** are connected to the emitter electrodes **46e** and **45e**.

In the operation of the illustrated NPN transistor threshold logic circuit, V_{PS} has a value more negative than the ground reference **G**, and V_{ref} has a value in between V_{PS} and **G**, whereby V_{ref} can be obtained by means of a voltage divider. In addition the signal voltages X_1 through X_n , V_0 and $\bar{V}_0$ have either high (HI) or low (LO) values relative to V_{ref} . For the purpose of the description which follows, the HI and LO signals are considered as 1 and 0 signals, respectively.

Referring in particular to the operation of the comparator **10₁**, the voltage V_{PS} and the common emitter resistor **13** simulate a source of current for the current switches, e.g., transistors **11** and **12**. Whenever the applied signal voltage X_1 is a 1 signal, transistor **11** is turned on and the transistor **12** is turned off. The current source current is routed through the collector-to-emitter path of transistor **11**, the output line **17** and the load resistor **31**. On the other hand, when the applied signal voltage X_1 is a 0 signal, the transistor **12** is turned on and the transistor **11** is turned off. For this input signal condition, the current source current is routed through the collector-to-emitter path of the transistor **12**, the output line **18** and the load resistor **32**.

Each of the other input comparators respond to their applied input signals to provide their respective current contributions to the output line **17** or **18**, according to whether the respective input voltages are 1 or 0 signals. The current contributions of the individual input comparators may be different according to binary input weighting factors. For example, the i th binary input may have a weight w_i , where w_i is an integer. The inputs can be weighted, for instance, by applying the same input signals to two or more input lines. Thus, when $n=5$, if one signal is applied to two of the 5-input lines, a (2111) gate results—weights respectively 2, 1, 1 and 1. Another way of weighting the inputs is to divide the i th comparator emitter resistor **13** by the weight w_i as, for example, by connecting w_i resistors of equal value in parallel.

The output current contributions of the comparators are effectively summed by the load resistors **31** and **32** with the difference therebetween being detected by the threshold discriminator **35** to provide the output signals V_0 and $\bar{V}_0$. It should be noted that the total current flow in the load resistors is always the same but is differently distributed in accordance with the input signals.

In a 7-input majority gate ($n=7$, and all weights are unity) by way of example, there are 7 units of current distributed between the lines **17** and **18**. When all 7 input signal voltages are 1 signals, 7 units of current are routed through line **17** and no units of current are routed through line **18**. On the other hand, when all 7 input voltages are 0 signals, 7 units of current are routed through line **18** and no units of current are routed through line **17**. In such a gate the closest decision (comparison with threshold) is determined when the current distribution is 4 units in one line and 3 units in the other line.

The routing of current in the output CMS comparator is controlled by the difference in current flow in lines **17** and **18**, i.e., the difference in voltage drops across resistors **31** and **32**. For the preceding 7-input majority gate example, the output comparator current routing is switched between alternate current paths provided by the output CMS transistors **40** and **41** as the input signals change from 3 or less "1" signals to 4 or more "1" signals or from 4 or more "1" signals to 3 or less "1" signals.

One of the principal features of the current mode switch comparators is that they can be operated in a nonsaturated manner, thereby contributing to high-speed operation. In a threshold logic circuit as described above, the summed current contributions cause IR voltage drops across the load resistors **31** and **32**. For some circuit designs, the voltage drops render the comparator output lines **17** and **18** sufficiently negative to saturate the transistors in the input comparators **10₁** through **10_n** or sufficiently positive to saturate the output CMS comparator transistors depending upon the distribution of the input comparator current contributions between the lines **17** and **18**. The network of the present invention enables circuit designs which limit the current distribution and therefore the voltage drops across the summing load resistors **31** and **32** to the closest decision case, which for the 7-input majority gate is 4 current units in one line and 3 current units in the other line. That is, the limiting network not only

prevents one line from becoming too low, but also prevents the other line from becoming too high, thereby tending to prevent saturation of both the input and output CMS transistors.

The limiting network 20 operates as follows. The values of resistors 13, 31, 32 and sources V_{ref} , V_{PS} and V_{CL} are selected so that for the closest decision case neither the transistor 21 nor the transistor 22 is turned on. For this case, the voltages V_A and V_B at lines 17 and 18 are primarily a function of the IR voltage drops across load resistors 31 and 32. For the 7-input majority gate example where four of the inputs are 1 (HI) signals, the voltage V_A is -4 IR volts, where I is defined as a unit of current and R is defined as the value of load resistor 31. This value for V_A is chosen to be sufficiently positive to provide a reliable margin of saturation prevention.

The voltage V_{CL} is suitably chosen so that when current distribution deviations from the closest decision case cause either the voltage V_A or the voltage V_B to become more negative, the corresponding transistor 21 or 22 turns on. For example, where more than four 1-input signals are applied, more units of current tend to flow through resistor 31 and less units of current flow through resistor 32. The voltage V_A tends to become more negative; while the voltage V_B tends to become more positive. However, transistor 22 turns on to limit the amount of current drawn through the load resistor 31 and thereby limit the voltage V_A . Transistor 22 draws collector current by way of load resistor 32, thereby tending to make V_B more negative or tending to limit the positive or high voltage excursion thereof. On the other hand, the emitter current of transistor 22 flows to the ON transistors 11 of the input comparators. In other words, transistor 22 responds to more than four 1-input signals to draw current through load resistor 32 and supply current to line 17 and the ON transistors 11 to thereby limit both V_A and V_B . For current distributions corresponding to less than three 1-input signals, the transistor 21 operates similarly to limit the current flow in resistor 32.

The base resistors 23 and 24 are provided for the purpose of limiting the base current to transistors 21 or 22. In the case above where there are more than four "1"-input signals, it is desired that current flow in the collector-to-emitter circuit of transistor 22. However, the characteristics of some NPN transistors will also permit some current to flow in the base-to-collector circuit and the emitter-to-collector circuit of transistor 21. This current is undesirable since the current gain of some transistors operated in this mode is near unity. In order to limit this current, resistors 23 and 24 are provided.

Referring now to FIG. 2, another embodiment of the invention includes a voltage clamping V_{CL} control circuit 50 for use with the limiting network 20. Since the limiting network, current carrying lines and threshold logic circuit bear physical resemblance to the FIG. 1 circuit, like reference characters denote like components.

Certain modifications from the FIG. 1 threshold logic circuit are illustrated in FIG. 2 for the purpose of demonstrating the use of the V_{CL} circuit with threshold logic circuits as described in the aforementioned copending application of Robert O. Winder. As described therein, the load or summing resistors for the input comparators may be comprised of n parallel-connected resistors, where n is the number of input comparators. Thus, load resistors 31 and 32 are shown as having parallel-connected resistors $31_1, 31_2, \dots$ and 31_n and $32_1, 32_2, \dots$ and 32_n , respectively. In order to simplify the illustration and conserve space on the drawing, the input comparators are not shown in detail. Instead, the lines 17 and 18 are designated as being connected to each of the comparators by the reference characters $10_1, 10_2, \dots$ and 10_n .

Also as described in the copending application, the output lines 17 and 18 are connected by way of emitter-

follower transistors 60 and 61 to output terminals 36 and 37, also designated V_0 and $\bar{V}_0$, respectively. To this end, the base electrodes 60b and 61b are connected to lines 18 and 17, respectively; the collector electrodes 60c and 61c are connected to the ground line G; and the emitter electrodes 60e and 61e are connected to the output terminals 36 and 37, respectively. The emitter electrodes 60e and 61e are further connected by way of emitter resistors 62 and 63 to the V_{PS} line.

The function of discrimination (comparison with threshold) is performed by the input comparator of the next or driven stage or stages which is or are connected to the output terminals 36 and 37 as described in the copending application. In accordance with the description therein, the logic signals for the FIG. 2 circuits are such that any signal voltage values above (more positive than) the reference voltage V_{ref} are of a first binary significance and any signal voltage values below (more negative than) V_{ref} are of a second binary significance. For the purpose of the description which follows, these first and second binary significances are arbitrarily considered as binary 1 and binary 0 signals.

The voltage clamping control circuit 50 includes three transistors 51, 52 and 53 arranged in an emitter-coupled, current mode configuration. To this end, the emitter electrodes 51e, 52e and 53e are coupled together and by way of a common emitter resistor 54 to the V_{PS} line. The collector electrodes 51c and 53c are coupled by way of negligible impedance means to the ground line G; while the collector electrode 52c is connected by way of a collector resistor 55 to the ground line G. The collector electrode 52c is further connected to the V_{CL} circuit point for the limiting network 20. The base electrodes 51b and 53b are connected to the output terminals 36 and 37, respectively, while the base electrode 52b is connected to receive a reference voltage V_R which may be different from V_{ref} . The reference voltage V_R may be derived from the V_{PS} and ground G lines by way of a voltage divider. The voltage divider is illustrated as including a first resistor 56 connected between the ground line G and the base electrode 52b and a second resistor 57 connected between the V_{PS} line and the base electrode 52b.

In operation, if either the output V_0 or $\bar{V}_0$ rises above (becomes more positive than) V_R , the clamp voltage V_{CL} rises, thereby causing more current flow between the lines 17 and 18 when either transistor 21 or 22 is conducting. For the 7-input majority gate example, the closest decision case is the 4:3 current distribution between the lines 17 and 18. For this case, the clamp voltage V_{CL} is of such value that neither transistor 21 nor transistor 22 is conducting as described for the FIG. 1 circuit. That is, the output V_0 or $\bar{V}_0$, as the case may be, which is above V_R is not sufficiently positive to cause V_{CL} to rise enough to turn on either of the transistors 21 or 22.

For current distributions of more than four 1-input signals, the line 18 becomes more positive. The output V_0 rises causing V_{CL} to rise, whereby transistor 22 turns on. As more and more 1 signals are applied, V_{CL} tends to rise even more causing transistor 22 to conduct more and more current. That is, transistor 22 tends to draw more current through the load resistor 32 and supply more current to line 17.

For current distributions corresponding to less than three 1-input signals, the line 17 becomes more positive, the output $\bar{V}_0$ rises, thereby causing V_{CL} to rise, and since V_A is more positive than V_B transistor 21 turns on. As less and less 1 signals are applied, V_{CL} tends to rise even more causing transistor 21 to conduct more and more current.

In summary, the V_{CL} control circuit responds to the output signals V_0 and $\bar{V}_0$ to cause the clamp voltage V_{CL} to render the ON one of the transistors 21 and 22 more or less conductive according to the input signal combinations, thereby maintaining the outputs within set limits and preventing saturation of the CMS input com-

parators for this stage as well as for the succeeding or driven stage.

The invention has been illustrated with NPN transistors by way of example only and is not limited in application to the use thereof. For instance, PNP transistors or other amplifying devices may also be used in the practice of the invention, provided that appropriate signal and bias voltages are accordingly altered.

What is claimed is:

1. In combination: 10
a current source;
a pair of current carrying lines coupled to said source, each for carrying a portion of the source current;
an impedance in each line for developing a voltage proportional to the flow of current through its line;
a pair of amplifying devices direct-current connected in parallel across said lines, one connected to carry current in the one direction and the other connected to carry current in the opposite direction; and
means for biasing said amplifying devices at a level such that when the voltage at one line exceeds that at the other by more than a given value, current flows between the two lines in one direction through one amplifying device and when the voltage at the other line exceeds that of the one line by more than said given value, current flows between the two lines in the opposite direction through the other amplifying device. 20
2. The invention according to claim 1
wherein the amplifying devices are transistors having collector-emitter paths corresponding to the conduction paths and having base electrodes corresponding to the control electrodes. 30
3. The invention according to claim 2
wherein the first and second transistors are of like conductivity, and
wherein the collector electrode of the first transistor is connected to the emitter electrode of the first transistor and vice versa. 35
4. The invention according to claim 3, further including a resistor in series with each base electrode. 40
5. A network for apparatus wherein input means selectively distributes current to a pair of current carrying lines, said network comprising:
first and second amplifying devices, each having a conduction path connected across the lines and each having a control electrode;
means for coupling the control electrodes to a control voltage; 45
said input means having a number n of input current mode comparators for distributing current to the lines in accordance with various input signal combinations which are applied to the comparators; and
each line including a summing impedance. 50
6. The invention according to claim 5
wherein the amplifying devices are transistors having collector-emitter paths corresponding to the conduction paths and having base electrodes corresponding to the control electrodes, 55
wherein the control voltage is derived from a control circuit which includes
third, fourth and fifth transistors connected in an emitter-coupled current mode comparator configuration,
means for coupling the base electrodes of the third and fourth transistors to different ones of the summing impedances, 60
5. The invention according to claim 6
wherein sixth and seventh emitter-follower transistors couple different ones of the summing impedances to the base electrodes of the third and fourth transistors, respectively. 65
- 8
- means for coupling the base electrode of the fifth transistor to a reference voltage, and
means for obtaining the control voltage from the collector electrode of the fifth transistor.
7. The invention according to claim 6
wherein sixth and seventh emitter-follower transistors couple different ones of the summing impedances to the base electrodes of the third and fourth transistors, respectively.
8. The combination comprising:
first and second lines for carrying current, each line producing a voltage drop proportional to the current therethrough;
input current switching means having at least one input node adapted to receive input signals and first and second outputs coupled, respectively, to said first and second lines for distributing a relatively constant current between said lines;
bidirectional current carrying means having conduction path means coupled between said two output lines and a control means separate from said conduction path means for controlling the conductivity of said conduction path means; and
means for applying a control signal to said control means for causing said bidirectional means to divert current from the one of the lines carrying the lesser current to the line carrying the greater current when the voltage drop of the latter exceeds a given value of potential.
9. The combination as claimed in claim 8
wherein said bidirectional current carrying means includes two transistors having their conduction paths connected in parallel and their control electrodes connected to said means for applying a control signal.
10. In combination with a differential amplifier stage having: (a) first and second differential input signal terminals, (b) a common impedance element for carrying the current of said stage, and (c) first and second differential outputs for producing complementary signals in response to signals applied at said input terminals, the improvement comprising:
amplifying means having a conduction path and a control electrode separate from said conduction path for controlling the conductivity of said path;
means for applying a bias voltage to said control electrode; and
means directly connecting said conduction path between said differential outputs for causing said conduction path to carry current from one differential output to the other when the potential at the latter exceeds said bias potential.
